UNITED STATES PATENT OFFICE.

DANIEL KOPS, OF NEW YORK, N. Y., ASSIGNOR TO KOPS BROS. INC., OF NEW YORK, N. Y., A CORPORATION OF NEW YORK.

APPAREL GARMENT.

Application filed June 17, 1922. Serial No. 562,927.

To all whom it may concern:

Be it known that I, DANIEL KOPS, a citizen of the United States, residing in the borough of Manhattan, city, county, and 5 State of New York, have invented an Improvement in Apparel Garments, of which the following is a specification.

My present invention relates to an apparel garment and more particularly to that 10 type of apparel corset shown and described in Letters Patent No. 1,432,470, October 17, 1922. The style of apparel corset to which the invention relates is a closed back garment and one in which in the front portions 15 of the garment there are elastic sections extending from the upper to the lower edges thereof with underlying adjusting devices by which the garment is adjusted to position on the body by effecting a pull or tension at the sides which extend therefrom in both directions.

The object of the invention in the present case is the provision in a garment of this type of a back construction which provides 20 a yielding support for the small of the back and also provides a pocket or receptacle at the upper back portion of the garment to yieldingly receive and support the flesh of the body which would otherwise overlie the 25 top edge of the garment and form a rib or ridge of unsightly appearance. In carrying out the invention in the present case the garment includes a body member having a back central section in which there may be 30 placed an elastic insert centrally overlying the small of the back, and in the central back section there are sets of stays diverging upwardly so as to provide at the top of the garment when coacting with elastic inserts 35 which are also placed on either side of the central back section a pocket for receiving and supporting the flesh of the body at the upper edge of the garment. The garment also includes in the front portions thereof 40 the elastic sections as aforesaid, together with the underlying adjusting devices for effecting the adjustment as hereinbefore stated.

In the drawing:

50 Fig. 1 is a perspective view illustrating a corset made in accordance with this invention.

Fig. 2 is a plan of the garment.

55 Fig. 3 is an enlarged elevation of the upper part of the back portion of the corset.

Fig. 4 is an enlarged section on line 4—4, Fig. 2.

Fig. 5 is an enlarged cross section on line 5—5, Fig. 2.

Fig. 6 is an elevation showing the inner 60 portion at one end of the garment to illustrate the construction of the adjusting devices, and

Fig. 7 is a partial elevation showing another form of construction of the back member 65 of the garment.

Referring particularly to the drawing, the garment made in accordance with this invention comprises the usual front steels 10 and 11. The front steel 10 is fitted in the 70 customary manner with studs 12, and the steel 11 with eyes or hooks 13 by which the front steels are connected when the garment is in use. The front steel section 10 includes a downward extension 14, and similarly the front steel section 11 includes a downward extension 15. In the extension 14 there are series of eyelets 16, and in the extension 15 a corresponding series of eyelets 17. These eyelets 16 and 17 may have 80 a suitable lace threaded through the same so that they may be connected when the garment is in use. The extension 14 is provided with a catch 18 and the extension 15 with a hook 19 by which these extensions 85 may also be connected immediately below the lower ends of the front steels of the garment. In the left hand forward end of the garment there is an elastic section 20 made of any suitable elastic fabric. This section 90 extends from the upper to the lower edge of the corset and along its forward edge it is connected to the front steel section 10 by a line of stitching 21. At its opposite edge it is connected to the forward side section 22 95 by a line of stitching indicated at 23. Similarly in the right hand forward end of the garment there is an elastic section 24 corresponding with the elastic section 20. At its forward edge this elastic section 24 is connected to the front steel section 11 along a line of stitching 25 and at its opposite edge 100 is connected to the forward side section 26 by a line of stitching 27.

The body of the garment includes a central back section indicated at 28. In this back section 28 and in spaced substantially parallel positions on opposite sides of the center line there are stay members 29 and 30. Also in this central back section and 105 110

adjacent the edges thereof there are stay members 31 and 32. These preferably diverge upwardly relatively to the stays 29 and 30. Centrally disposed in this central back section I employ an elastic insert indicated at 33. This is placed so as to extend over the central line of the back section between the stay members 29 and 30 and to overlie the small of the back of the wearer. This elastic insert 33 is secured in the garment by being stitched along its opposite edges as indicated at 34 and 35, while the upper and lower ends thereof are not connected to the garment.

15 The body of the garment also includes the rearward side sections 36 and 39. The section 36 is connected along one edge to the section 22 by lines of stitching indicated at 37, and along its opposite edge this section 36 is connected to the central back section along lines of stitching indicated at 38. Similarly the rearward side section 39 is connected to the central back section along one edge thereof by a line of stitching indicated at 40, and at the opposite edge this section 39 is connected to the section 26 along lines of stitching indicated at 41. The sections 36 and 39 terminate short of the upper edge of the garment and are completed by 20 elastic inserts 42 and 43 made of any suitable elastic or other elastic fabric. These inserts are connected to the sections 36 and 39 by suitable lines of stitching and are connected at their ends to the central back section and the sections 22 and 26 respectively by the same lines of stitching which connect the sections 36 and 39 thereto.

25 In the left hand end of the garment underlying the elastic section 20 there are inelastic adjusting devices. These adjusting devices include a strap 44 which along one edge is connected to the front steel section by the line of stitching 21. Along its opposite edge the strap 44 is provided with a series 30 of eyelets 45. The adjusting devices also include an anchor strap 46 secured along one edge to the section 22 by the line of stitching 23, and along its opposite edge this anchor strap 46 is provided with a series of eyelets 47. Threaded through the eyelets 45 and 47 is a lace 48 by which is also threaded through eyelets 49 so as to pass to the exterior of the garment from which position the parts may be adjusted.

35 In the same manner in the right hand end of the garment, the inelastic adjusting devices comprise a strap 50 secured along one edge to the front steel section 11 by the line of stitching 25 and provided along its opposite edge with a series of eyelets 51. These adjusting devices also include an anchor strap 52 which along one edge is connected to the section 26 by the line of stitching 27, and along its opposite edge this anchor strap 52 is provided with a correspond-

ing series of eyelets 53. A lace 54 is threaded through the eyelets 51 and 53 and also through eyelets 55 to extend through the exterior of the garment.

From the foregoing description it will now be understood that the apparel garment hereinbefore described after being placed on the body of the wearer is adjusted to position by drawing up and tying the laces 48 and 54 which determine the respective 70 positions of the adjusting devices at the front of the garment and by which a tension or pull is exerted in both directions, that is from the front section of the garment rearwardly and from the back section of the 75 garment forwardly. It will also be understood that the back insert 33 overlies the small of the back of the wearer and that this, together with the other features of the construction of the back central member and the elastic inserts at the upper ends of the 80 rearward side members provide a pocket at the top of the back of the garment for receiving and supporting the flesh of the wearer which would otherwise extend over 85 the edge of the garment.

90 By reference to Fig. 7, it will be seen that in some instances the yielding insert member 33 may be entirely dispensed with, and in such instances the construction of the back member is otherwise precisely the same as that hereinbefore described.

95 It will be understood that with the exception of the parts hereinbefore described as elastic the members of the garment are made of the usual inelastic corset material.

100 I claim as my invention:

1. In an apparel corset, front steel sections, elastic sections adjacent the front steel sections and extending from the upper to the lower edges of the garment, a back central section, an elastic insert in the back central section and adapted to overlie the small of the back of the wearer, and adjusting devices underlying the said elastic sections at the front of the garment whereby in the adjustment of the garment to position a pull is effected at the sides in both directions circumferentially of the garment.

110 2. In an apparel corset, front steel sections, elastic sections adjacent the front steel sections and extending from the upper to the lower edges of the garment, a back central section, an elastic insert therein and adapted to overlie the small of the back of the wearer, stays placed on either side of the said insert in the back central section, and adjusting devices underlying the said elastic sections at the front of the garment whereby in the adjustment of the garment to position a pull is effected at the sides in both directions circumferentially of the garment.

120 3. In an apparel corset, front steel sections, elastic sections adjacent the front

- steel sections and extending from the upper to the lower edges of the garment, a back central section, an elastic insert secured along its opposite edges in a centrally disposed position in the back central section, stays on both sides of the said insert and extending in upwardly diverging positions in the back central section, rearward side sections connected to the said back central section and each having an insert of elastic material at the upper end thereof, the said inserts in the said rearward side sections and the diverging stays in the back central section coacting to form a pocket at the upper edge of the garment for yieldingly supporting the flesh of the wearer, and adjusting devices underlying the said elastic sections at the front of the garment whereby in the adjustment of the garment to position a pull is effected at the sides in both directions circumferentially of the garment.
4. In an apparel corset, front steel sections, elastic sections adjacent the front steel sections and extending from the upper to the lower edges of the garment, a back central section, an elastic insert secured along its opposite edges in a centrally disposed position in the said back central section, stays on both sides of the said insert diverging toward the upper end of the garment to form a pocket at the upper end of the said back central section, and adjusting devices underlying the said elastic sections at the front of the garment whereby in the adjustment of the garment to position a pull is effected at the sides in both directions circumferentially of the garment.
5. In an apparel corset, front steel sections, elastic sections adjacent the front steel sections and extending from the upper to the lower edges of the garment, a back central section, an elastic insert secured along its opposite edges in a centrally disposed position in the said back central section, stays on both sides of the said insert diverging toward the upper end of the garment to form a pocket at the upper end of the said back central section, and adjusting devices underlying the said elastic sections at the front of the garment whereby in the adjustment of the garment to position a pull is effected at the sides in both directions circumferentially of the garment.
6. In an apparel corset, front steel sections, elastic sections adjacent the front steel sections and extending from the upper to the lower edges of the garment, a back central section, an elastic insert secured along its opposite edges in a centrally disposed position in the said back central section, stays on both sides of the said insert and extending in upwardly diverging positions in the back central section, rearward side sections connected to the said back central section and each having an insert of elastic material at the upper end thereof, the said inserts in the said rearward side sections and the diverging stays in the back central section coacting to form a pocket at the upper edge of the garment for yieldingly supporting the flesh of the wearer, and adjusting devices underlying the said elastic sections at the front of the garment whereby in the adjustment of the garment to position a pull is effected at the sides in both directions circumferentially of the garment.

Signed by me this 20th day of May, 1922.

DANIEL KOPS.
